COAL SHOVEL

John H. Fisher, Elyria, Ohio

Application July 13, 1933, Serial No. 680,302

1 Claim. (Cl. 209—418)

This invention relates to coal shovels and has for its object the provision of a tool which may be easily handled and by the use of which ashes may be separated from cinders and unburnt coal which may have collected in the ash pit of a furnace.

A further object of the invention is to provide a simple and inexpensive construction whereby the screen will be firmly retained in the shovel or scoop while in use and may be easily detached when its removal is desired.

Other objects of the invention will appear incidentally in the course of the following description and the invention resides in certain novel features which will be particularly pointed out in the appended claim.

In the annexed drawing,

Figure 1 is a perspective view of a coal shovel embodying the present invention,

Figure 2 is a longitudinal section on a somewhat larger scale,

Figure 3 is a detail perspective view showing the construction of the screen, and

Figure 4 is a detail view of the removable journal.

The body 1 of the shovel is in the form of a scoop having a bottom, back and sides and having an open top and front, as clearly shown in the drawing. This body may be easily constructed of sheet metal stamped into the desired form and having its side portions extended transversely and overlapped at their ends to form the back member, as shown at 2. A short sleeve or socket 3 is also formed on the back member at the center thereof and the end of the handle 4 is received in said socket and secured therein by rivets, as indicated at 5. Near their upper rear corners, the sides of the scoop are provided with openings, indicated at 6, and from one of said openings rises a notch or open-ended slot 7, as shown.

The screen comprises a sheet of reticulated material, preferably woven wire, as shown at 8, and a reinforcing frame consisting of side and front members 9 and a back member 10. This frame is formed of sheet metal, the side and front members being in the form of reentrant flanges, as shown clearly at 11 in Figure 3 and the edges of the screen being folded inwardly on themselves and inserted between the members of the flange and then secured rigidly therein by crimping or compressing the members of the flange. The back member 10 rises from the frame and has secured thereto by nails, rivets, or other suitable fastenings, a rod 12 which is of circular cross

section through the greater portion of its length, one end being reduced and formed with flat sides to produce a trunnion 13 which may pass through the slot or notch 7 to position the rod in the shovel or remove it therefrom.

The screen is of such length that, when it is in position within the shovel or scoop, the front edge thereof will rest upon the bottom of the shovel at the front edge of the same, as indicated in Figure 1 and by dotted lines in Figure 2. In this position of the parts, as the shovel is pushed into a pile of ashes, the ashes will pass through the screen and collect in the lower portion of the shovel while the cinders and unburnt coal will be retained upon the screen, as will be understood. If it seems necessary, the tool may be shaken slightly so that any ashes which do not pass at once through the screen will be caused by the agitation to separate from the cinders and coal and pass into the space below the screen. The coal and cinders may roll from the screen after they have been relieved of the retarding influence of the ashes and the ashes may then be discharged at a suitable dumping place after the screen has been first turned upwardly and backwardly about the rod 12 as a center whereupon the free edge of the screen will rest upon the handle, as shown by full lines in Figure 2.

In applying the screen to the shovel, the axle or rod 12 is positioned with the flat sided trunnion or stem 13 alined with the notch or slot 7 so that the rod may be easily pushed to position within the shovel, after which a slight endwise movement will permit the round end of the rod to be engaged in the opening 6, provided therefor in the side of the shovel. The screen will then be swung down to the working position and this movement will cause the flat sided trunnion 13 to assume a position transverse to the slot or notch 7, as shown in Figures 1 and 4, so that the screen cannot be accidentally released from the shovel. It will be understood, of course, that the flat sided trunnion 13 is somewhat longer than the thickness of the material of the shovel so that if the round portion of the rod 12, at the base of said flat sided trunnion, be disposed against the inner face of the side of the scoop or shovel, the screen may be easily moved downwardly to its working position and will be secured in place by the slight endwise movement of the rod, which has been mentioned.

From the foregoing description, taken in connection with the accompanying drawing, it will be seen that I have provided an exceedingly sim-

ple and inexpensive tool whereby the labor of sifting ashes will be expedited, and when desired the screen may be very easily removed from the shovel.

5 Having thus described the invention, I claim:

A coal shovel comprising a scoop having pivot openings in its sides at the upper rear corners thereof and a slot rising from one of said openings through the upper edge of the side of the 10 scoop, a handle secured on the back end of the scoop at the bottom thereof and extending upwardly and rearwardly therefrom, a screen, a reinforcing frame secured around the edges of the screen and having its rear end extended rel-

atively upward for the full width of the frame, and a straight pivot rod secured rigidly to the free edge of the extended rear end of the frame with its ends projecting beyond the sides of the frame, one end of said rod having flattened sides whereby it may pass through the slot in the edge of the scoop and rotatably seat in the opening below the slot and the opposite end of the rod being circular in cross section whereby it may rotatably seat in the opening in the adjacent side of the scoop upon endwise movement of the rod and screen after the flat-sided end of the rod is seated. 5 10
